(57) **CLAIM**

The ornamental design for a welding tip for spot welding machine using copper tape, as shown and described.

DESCRIPTION

FIG. 1 is a perspective view of a welding tip for spot welding machine using copper tape according to my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of a welding tip for spot welding machine using copper tape, in an environment of use.

The broken lines seen in FIG. 7 show portions of a welding tip for spot welding machine using copper tape which form no part of the claimed design.

The broken lines seen in FIG. 8 are for the purpose of showing environmental structure, and form no part of the claimed design.

1 Claim, 8 Drawing Sheets
